UNITED STATES PATENT OFFICE

2,437,514

TOOL FOR CUTTING INSULATION ON
ELECTRIC CONDUCTORS

Glenn G. Givens, Newport News, Va.

Application January 23, 1946, Serial No. 642,809

3 Claims. (Cl. 30—91)

1

The present invention relates to a new and useful improvement in cutting tools for use on electric conductors for cutting the insulation covering the same and the invention has for its primary object to provide a tool of this character including a cutter mounted at the end of the tool and projecting into a transverse opening therein for cutting the insulation covering an electric conductor when positioned in said opening.

An important object of the invention is to provide means for mounting the cutter in the tool for adjustment whereby the insulation covering may be cut either longitudinally or circumferentially of the conductor.

A still further object of the invention is to provide a slideable mounting for the cutter adapted for engagement by the thumb of a person for exerting the necessary pressure against the insulation covering during the cutting action.

Another object of the invention is to provide a hand-gripping body having cutters of duplicate construction mounted in each end thereof and associated with transverse openings in the body of different sizes to accommodate wires of different diameters.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a similar view taken at right angles to Figure 1 and showing the transverse openings in the opposite ends of the body of the tool.

Figure 3 is a longitudinal sectional view taken substantially on a line 3—3 of Figure 1.

Figure 4 is an enlarged longitudinal sectional view of one of the caps and cutter mounted therein.

Figure 5 is a transverse sectional view taken on a line 5—5 of Figure 3.

Figure 6 is a side elevational view of the tubular blade holder sleeve.

Figure 7 is a longitudinal sectional view taken on a line 7—7 of Figure 6.

Figure 8 is an elevational view of the inner end of the blade holder sleeve.

Figure 9 is a longitudinal sectional view of the adjustable blade holding member.

Figure 10 is a similar view taken on a line 10—10 of Figure 9.

Figure 11 is an end elevational view of the lower end of the blade holding member.

Figure 12 is a perspective view of the blade.

2

Figure 13 is a side elevational view of the retaining bushing for the blade, and

Figure 14 is a side elevational view of the adjusting screw for the blade.

Referring now to the drawings in detail wherein for the purpose of illustration I have disclosed a preferred embodiment of the invention. The numeral 5 designates the elongated body of the tool which is of cylindrical construction and formed with an enlarged end 6 at one end thereof.

A transverse opening 7 is formed in the enlarged end portion of the body and a similar transverse opening 8 is formed near the opposite end of the body, the openings being adapted to receive electric conductors 9 therein of different diameters, the conductors being of the usual type provided with a natural or synthetic rubber insulation covering 10.

Caps 11 and 12 are telescopically mounted on the opposite ends of the body, each cap being provided with a cutter designated respectively at 13 and 14, the cutters being of identical construction and accordingly a detailed explanation of one will suffice for both.

The cutter embodies a cutter holding sleeve 15 having one end projecting through the top of the cap 11 and welded or otherwise suitably secured thereto as indicated at 16. The outer end of the sleeve is internally threaded as shown at 17 for threadedly receiving an adjusting screw 18 therein.

The inner end of the sleeve is closed as indicated at 19 and formed with a transverse slot 20 and in which a flat blade 21 is slidably received. One end of the blade is pointed as indicated at 22, while the other end of the blade is formed with a cross head 23 which has its ends projecting outwardly from the opposite side edges of the blade.

A bushing 25 is positioned in the inner end of the sleeve 15 with one end resting on the closed end 19 and with notches 26 formed in its other end at diametrically opposite sides receiving the ends of the cross head 23.

A tubular blade holder 27 is slidably mounted in the sleeve 15, the lower end of the blade holder being formed with a bifurcated extension 28 of reduced diameter and in which the inner end of the blade 21 is received.

The inner end of the adjusting screw 18 is formed with a reduced extension 29 having an external annular groove 30 formed therein for receiving a set-screw 31 threaded through an opening 32 in one side of the tubular holder 27.

The extension 29 on the inner end of the adjust-

ing screw 18 is mounted for rotation in the tubular blade holder 27 during the rotation of the screw during its adjustment while the blade holder 27 is held against rotation by the blade in the slot 20 of the sleeve 15. The inner end of the sleeve 15 is slidably received in a bushing 33 positioned in a longitudinal opening 34 in the end of the body 5, the bushing being secured against the rotation by means of a set screw 40. A spring-actuated plunger 35 is mounted in a transverse opening 36 in the body and having a tip 35a projected through an opening 37 in one side of the bushing by means of a coil spring 38. The spring is held in the opening 36 by means of a screw 39. The tip 35a is projected into longitudinal grooves 42 formed in the sides of the sleeve 15 at angles of 90 degrees to retain the sleeve in rotatably adjusted position in the bushing whereby to position the blade 21 either transversely or longitudinally with respect to the cable 15 for cutting the cable either longitudinally or circumferentially.

The adjusting screw 18 is formed with a bore 43 in its outer end in which a plug 44 is fixedly secured. The inner end of the plug is formed with a transverse groove 45 adapted to receive a cross head 46 carried at the inner end of a stem 47 slidably mounted in the plug and having a knob 48 secured to its outer end. By pulling the knob outwardly to seat the cross head 46 in the groove 45 the screw may be rotated to adjust the screw 18 in the sleeve 15 and thus regulate the cutting depth of the blade 21.

In the operation of the device the blade 21, bushing 25, blade holder 27 and adjusting screw 18 are mounted in assembled relation in the sleeve 15 in the manner as illustrated in Figure 4 of the drawings with the inner end of the blade projecting from the inner end of the sleeve and the sleeve being carried by the cap 11.

The sleeve 15 and cap 11 are then rotatably adjusted in the body so that the pointed end of the blade will extend either longitudinally of the opening 7 or transversely thereof depending upon the character of cut to be made in the insulation 10. Where the insulation is to be cut longitudinally, the cutter 21 is positioned longitudinally in the opening and where a circumferential cut is to be formed in the insulation, the cutter is positioned transversely of the opening 7. The sleeve 15 is secured in its adjusted position against rotation by means of spring projected tip 35a on the plunger 35 engaged in the grooves 42 of the sleeve 15.

The cutting tool is then held in the hand of a person with the thumb bearing against the cap 11 to exert a desired pressure on the blade 21 and by sliding the conductor 9 transversely of the body 5 the insulation will be cut longitudinally, or by rotating the conductor in the opening 7 the

insulation will be cut circumferentially, the blade being adjusted in accordance with the character of the cut to be made in the insulation.

In view of the foregoing description taken in conjunction with the accompanying drawings it is believed that a clear understanding of the construction, operation and advantages of the device will be quite apparent to those skilled in the art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

I claim:

1. A wire stripper comprising an elongated body having a transverse opening adapted to receive an insulated wire therein, a sleeve slidably mounted in the body for longitudinal movement thereof, a blade holder mounted for longitudinal sliding movement in the sleeve, a blade carried by the holder, and an adjusting screw threaded in the sleeve and connected to the blade holder for adjusting the blade relative to the wire.

2. A wire stripper comprising an elongated body having a transverse opening adapted to receive an insulated wire therein, a sleeve slidably mounted in the body for longitudinal movement thereof, a blade holder mounted for longitudinal sliding movement in the sleeve, a blade carried by the holder, an adjusting screw threaded in the sleeve and connected to the blade holder for adjusting the blade longitudinally in the sleeve relative to the wire, and an interlocking manipulating member mounted in the screw for sliding interlocking engagement therewith.

3. A wire stripper comprising an elongated body having a transverse opening adapted to receive an insulated wire therein, a sleeve slidably mounted in the body for longitudinal movement thereof, a blade holder mounted for longitudinal sliding movement in the sleeve, a blade carried by the holder, an adjusting screw threaded in the sleeve and connected to the blade holder for adjusting the blade longitudinally in the sleeve relative to the wire, and a cap telescoping on the body and connected to the sleeve for subjecting the blade to manual cutting pressure.
